UNITED STATES PATENT OFFICE.

DANIEL McERLANE, OF MANKATO, MINNESOTA.

VENTILATING BOOTS AND SHOES.

1,255,451.

Specification of Letters Patent.

Patented Feb. 5, 1918.

Application filed December 6, 1915. Serial No. 65,378.

To all whom it may concern:

Be it known that I, DANIEL McERLANE, a citizen of the United States, residing at Mankato, in the county of Blue Earth and

5 State of Minnesota, have invented new and useful Improvements in Ventilating Boots and Shoes, of which the following is a specification.

10 The device forming the subject matter of this application is adapted to be employed for ventilating articles of footwear.

15 The invention aims so to construct an upright air passage in the leg and in the foot of an article of footwear, that the lower end of the passage will not be distorted as the foot of the wearer is crowded backwardly in walking.

20 Another object of the invention is to provide means whereby the entrance of dirt into the lower end of the passage will be avoided, the construction being such that air may readily pass into the interior of the article of foot wear from the lower end of the passage.

25 It is within the province of the disclosure to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed, without departing from the spirit of the invention.

In the accompanying drawings:—

40 Figure 1 shows in side elevation, an article of foot wear embodying the present invention;

Fig. 2 is a vertical section showing an article of foot wear wherein the present invention is embodied;

Fig. 3 is a top plan of the structure shown in Figs. 1 and 2; and

Fig. 4 is a fragmental cross section on the line 4—4 of Fig. 2.

In carrying out the present invention 50 there is provided an article of footwear including a leg S, and a foot T having an elevated instep R. A strip M is applied to each side of the leg S, on the interior of the leg, the strip extending downwardly to the 55 foot T. The strip M forms a passage a. The passage a is forwardly inclined toward the toe U of the foot T to prevent a distortion of the lower end of the passage a as the foot of the wearer crowds backwardly in 60 walking. The upper end of the passage a is open as indicated at b. The lower end of the passage a terminates directly above the instep R to permit the pumping of air into and out of the passage a as the instep of 65 the wearer yields. The lower end of the passage a is open as indicated at c.

Having thus described the invention, what is claimed is:—

An article of footwear comprising a leg 70 and a sole; and a single-layer tape-like strip of material formed separately from the leg and extended downwardly along the inside of the leg, the longitudinal edges of the strip being secured to the leg and the trans- 75 verse end edges of the strip being spaced from the leg to form an air passage which is open axially at its ends, the lower end of the strip being spaced above the upper surface of the sole. 80

In testimony that I claim the foregoing as my own, I have hereunto affixed my signature in the presence of two witnesses.

DANIEL McERLANE.
